[57] **CLAIM**

The ornamental design for a fireplace hearth cover, as shown and described.

DESCRIPTION

FIG. 1 is a perspective view of a fireplace hearth cover showing my new design, which cover is shown installed on a fireplace hearth;

FIG. 2 is a front elevational view thereof;

FIG. 3 is a right end elevational view thereof, the left end being a mirror image of that shown;

FIG. 4 is a rear elevational view thereof;

FIG. 5 is a top plan view thereof; and,

FIG. 6 is a bottom plan view thereof.

The broken-line showing of environmental structure in FIG. 1 is for illustrative purposes only and forms no part of the claimed design.

FIG. 4

FIG. 5

FIG. 6
